UNITED STATES PATENT OFFICE

2,329,124

GASEOUS ELECTRICAL DISCHARGE LAMP

Eugene Lemmers, Cleveland Heights, Ohio, assignor to General Electric Company, a corporation of New York

Application December 30, 1940, Serial No. 372,273

11 Claims. (Cl. 176—124)

My invention relates to gaseous electric discharge lamps and more particularly to a high pressure metal vapor lamp having an extended illuminating surface of high intrinsic brilliance.

In the past, gaseous discharge lamps have not been readily adaptable to certain fields of application, such as motion picture projection for example, because such fields generally require a source in which a large amount of light energy is concentrated within a small cross-sectional area if the optical systems of the apparatus involved are to produce clear images. Low pressure gaseous discharge lamps fail in this requirement because their light output per unit area of luminous surface is relatively small, i. e., they have low intrinsic brilliance. In recent years high pressure lamps of extremely high intrinsic brilliance, such as the so-called mercury vapor capillary lamps, have been developed. These, however, have not been entirely satisfactory for the reason that the high pressure tends to constrict the arc to a very fine thread and although the arc may have high intrinsic brilliance, it is, nevertheless, undesirable as a light source because of its geometrical configuration.

Now, I have found that the above disadvantage in high pressure lamps can be overcome by providing a lamp of the aforesaid high pressure type with a flattened arc chamber and by operating it under the conditions of pressure and current density hereinafter specified. When so operated the arc is not only made to spread out into a stable and highly brilliant source of substantial area but it is also caused to emit many new spectral lines which improve the general spectral quality of the lamp.

It is accordingly an object of my invention to provide an improved high pressure gaseous discharge lamp of high intrinsic brilliance and having a luminous surface of substantial area.

It is another object of my invention to provide an improved light source for projection and like purposes.

A still further object of the invention is to provide a lamp of improved spectral quality.

Further objects and advantages on the invention will become apparent from the following detailed description and the accompanying drawing in which Fig. 1 shows a view, partly in section, of a lamp constructed in accordance with the invention along with a circuit for operating the same, while Fig. 2 shows a cross-section taken along the line 2—2 of Fig. 1.

Referring to Fig. 1, the lamp 1 comprises an envelope 2, preferably of glass or quartz, in which

are sealed the electrodes 3—3 which may be of the type generally used in capillary lamps. For example, they may consist of a central core of thorium within a spiral coil of tungsten wire or they may be formed by a tungsten coil activated by a suitable material such as barium or strontium carbonate. They may even be of the liquid type formed by pools of mercury, for example, if means are provided for cooling them to a sufficiently low temperature to maintain the low vapor pressure required. If solid electrodes are used, a small amount of mercury or other suitable material provides a source of metal vapor and is inserted in the envelope 2 in the usual manner during the evacuation process. In addition, a small amount of an ignition gas may be added, for example 10 mm. of argon. As indicated by the cross-sectional view of Fig. 2, the envelope 2 is of flattened shape. The cross-section at the inner surfaces of the envelope may, for example, have dimensions of the order of $\frac{3}{8}'' \times .060''$. Energy for operation of the lamp may be provided by the secondary winding 8 of the leakage reactance transformer 9 which is energized by any suitable source of alternating current power 10 through the primary winding 11. The transformer provides the necessary ballast for the lamp.

In order that the pressure may be kept at the desired low value, it will generally be necessary that the vapor atmosphere be unsaturated during the operation, i. e., that insufficient mercury or other metal be present to furnish the amount of vapor which the envelope would normally hold in a vaporized state at the temperature of operation. This may be accomplished by limiting the quantity of material introduced into the envelope to such an extent that it is completely vaporized before the device attains its operating temperature. In this manner the normal operating pressure may be limited to any desired value. Of course, if an excess of mercury is used, the pressure may still be kept low by artificial cooling but this procedure is, of course, more difficult in practice.

Now I have found that a discharge between the electrodes 3—3 will flatten out to fill the entire envelope as desired only under certain conditions of gaseous pressure and current strength. These factors, I find, have opposite effects upon the arc, increasing pressure tending to restrict its cross-section and increased current density tending to enlarge it and vice versa. Thus, with high pressures such as obtain in the conventional type of high pressure capillary lamp, the arc will con-

centrate in a narrow thread 4 which follows approximately the shortest distance between the electrodes. As, however, the current strength is increased the arc will be forced to expand in order that it may obey its natural tendency to follow the path of least electrical resistance provided, of course, that the pressure is prevented from rising and thus exerting its constricting influence. Progressively flattened cross-sections of the arc as the current strength progressively increases at constant pressure are shown by dotted lines 5, 6 and 7. It is thus seen that if current strength is sufficiently increased, the arc may be forced to assume a broadened shape which will form a flattened luminous surface of the shape of the envelope and of intrinsic brilliance comparable with that of the conventional capillary lamp.

Generally speaking, the current necessary to flatten the arc will be roughly proportional to the pressure or to some low power thereof. I am unable at this time to state an exact relationship between the two factors. With very high pressures the current density necessary to flatten the arc becomes prohibitive for all practical purposes because with envelope materials presently available, the heat developed tends to melt the envelope. I would estimate the practical upper pressure limit for presently available materials to be not greater than about 10 atmospheres. It thus becomes necessary to reduce the pressure in order to flatten the arc at a current within the range of practicality. On the other hand, if too low pressures are resorted to, the light output per unit area is disadvantageously decreased since, as is wellknown, the light output from a gaseous discharge varies with pressure. I have found, for example, that at pressures below about one-half of one atmosphere, the light intensity or intrinsic brilliance is too low to be useful for such fields of application as motion picture projection. The upper limit of pressures is dependent largely on the materials available for cathode and envelope fabrication, i. e., the envelope must be made of a material which can withstand heating effect of the high current density necessary to flatten the arc. With the materials now available, the upper limit of pressure is of the order of 5 atmospheres. It will be understood, of course, that when new materials capable of withstanding the heat are found, lamps capable of employing the principles of the invention at pressures above the limits specified above may be constructed. In any event, it is thus necessary to strike a compromise between the limiting conditions of pressure and current if a current of practical value is to be used and a useful amount of light obtained.

I have constructed lamps with flattened chambers within pressure ranges of 0.5 to 5 atmospheres. With a pressure of 2 atmospheres and a $\frac{3}{8}'' \times 0.060''$ cross-section, 60 amperes or more were needed to flatten the discharge into the flat chamber. Thus, at 2 atmospheres, at least approximately 2700 amperes per square inch or 4 amperes per square millimeter are needed to fill the envelope of this size. For lamps with cross-sections of $0.005'' \times \frac{3}{8}''$ in the pressure range 0.5 to 5 atmospheres, the flattening would occur above 3 amperes or a current density of about 1600 amperes per square inch or 2.4 amperes per square millimeter.

It will be understood that any suitable cooling means as a liquid bath or air blast may be used

to aid in maintaining the low pressure. I have found the liquid bath most effective.

It will further be understood that the lamp herein disclosed is but one form of my invention and that many modifications within the scope of the appended claims may occur to those skilled in the art to which the invention appertains. For example, many different tube configurations may be employed. Further, other metallic vapors may be used, although in general the specified current densities and pressures will be changed somewhat if the same results are to be obtained. All such modifications I aim to include within the scope of the appended claims.

15 What I claim as new and desire to secure by Letters Patent of the United States is:

1. A gaseous electrical discharge lamp of the high pressure type comprising, an envelope having a flattened transverse cross-section, a pair of electrodes disposed within said envelope and capable of supporting a discharge therein longitudinally of the envelope, a quantity of vaporizable material in said envelope sufficient in amount to produce an operating vapor pressure of at least about 0.5 atmosphere, means for supplying sufficient electrical energy to establish said operating pressure and for supplying sufficient current between said electrodes to produce a discharge of sufficient density to cause the discharge to substantially fill said cross-section.

2. A gaseous electrical discharge lamp of the high pressure type comprising, an envelope having a flattened transverse cross-section, a pair of electrodes disposed within said envelope and capable of supporting a discharge therein longitudinally of the envelope, a quantity of vaporizable material in said envelope sufficient in amount to produce an operating vapor pressure of at least about 0.5 atmosphere, means for supplying sufficient electrical energy to establish said operating pressure and for supplying sufficient current between said electrodes to produce a discharge of sufficient density to cause the discharge to substantially fill said cross-section, said quantity of vaporizable material being insufficient to produce a saturated vapor atmosphere in said envelope at the normal operating temperature.

3. A gaseous electrical discharge lamp of the high pressure type comprising, an envelope having a flattened transverse cross-section, a pair of electrodes disposed within said envelope and capable of supporting a discharge therein longitudinally of the envelope, a quantity of vaporizable material in said envelope sufficient in amount to produce an operating vapor pressure of at least about 0.5 atmosphere, means for supplying sufficient electrical energy to establish said operating pressure and for supplying sufficient current between said electrodes to produce a discharge of sufficient density to cause the discharge to substantially fill said cross-section and cooling means for aiding the maintenance of the operating vapor pressure within practical limits, said quantity of vaporizable material being insufficient to produce a saturated vapor atmosphere in said envelope at the normal operating temperature.

4. A gaseous electrical discharge lamp of the high pressure type comprising, an envelope having a flattened transverse cross-section, a pair of electrodes disposed within said envelope and capable of supporting a discharge therein longitudinally of the envelope, a quantity of mercury in said envelope sufficient in amount to produce an operating vapor pressure of at least about 0.5

atmosphere, means for supplying sufficient electrical energy to establish said operating pressure and for supplying sufficient current between said electrodes to produce a discharge of a density of at least about 2.4 amperes per square millimeter, and cooling means for aiding the maintenance of the operating vapor pressure within practical limits.

5. A gaseous electrical discharge lamp of the high pressure type comprising, an envelope having a flattened transverse cross-section, a pair of electrodes disposed within said envelope and capable of supporting a discharge therein longitudinally of the envelope, a quantity of mercury in said envelope sufficient in amount to produce an operating vapor pressure of at least about 0.5 atmosphere, means for supplying sufficient electrical energy to establish said operating pressure and for supplying sufficient current between said electrodes to produce a discharge of a density of at least about 2.4 amperes per square millimeter, and cooling means for aiding the maintenance of the operating vapor pressure within practical limits, said quantity of mercury being insufficient to produce a saturated vapor atmosphere in said envelope at the normal operating temperature.

6. A gaseous electrical discharge lamp of the high pressure type comprising, an envelope having a flattened transverse cross-section, a pair of electrodes disposed within said envelope and capable of supporting a discharge therein longitudinally of the envelope, a quantity of mercury in said envelope sufficient in amount to produce an operating vapor pressure of the order of 0.5 to 5 atmospheres, means for supplying sufficient electrical energy to establish said operating pressure and for supplying sufficient current between said electrodes to produce a discharge of a density of at least about 2.4 amperes per square millimeter, said quantity of vapor being insufficient to saturate said lamp at its normal operating temperature.

7. A gaseous electrical discharge lamp of the high pressure type comprising, an envelope having a flattened transverse cross-section, a pair of electrodes disposed within said envelope and capable of supporting a discharge therein longitudinally of the envelope, a quantity of mercury in said envelope sufficient in amount to produce an operating vapor pressure of the order of 0.5

to 5 atmospheres, means for supplying sufficient electrical energy to establish said operating pressure and for supplying sufficient current between said electrodes to produce a discharge of a density of at least about 2.4 amperes per square millimeter and cooling means for aiding the maintenance of the operating vapor pressure within said pressure range, said quantity of vapor being insufficient to saturate said lamp at its normal operating temperature.

8. The method of operating a gaseous electric discharge lamp of the type having a flattened transverse cross-section between electrodes and a high vapor pressure, which comprises the steps of maintaining the pressure at a fixed value above about 0.5 atmosphere and passing sufficient current therethrough to cause the discharge to substantially fill said elongated cross-section.

10. The method of operating a gaseous electric discharge lamp of the type having a flattened transverse cross-section between electrodes and a high vapor pressure, which comprises the steps of maintaining the pressure within a range of the order of 0.5 to 5 atmospheres and passing sufficient current therethrough to cause the discharge to substantially fill said elongated cross-section.

20. The method of operating a gaseous electric discharge lamp of the type having a flattened transverse cross-section between electrodes and a high vapor pressure, which comprises the steps of maintaining the vapor in an unsaturated state at operating temperature and maintaining the pressure within a range of the order of 0.5 to 5 atmospheres and passing sufficient current therethrough to cause the discharge to substantially fill said elongated cross-section.

30. The method of operating a mercury vapor electric discharge lamp of the type having a flattened transverse cross-section between electrodes and a high vapor pressure, which comprises the steps of cooling said lamp to aid in maintaining the pressure within a range of the order of 0.5 to 5 atmospheres and passing a current of density of at least 2.4 amperes per square millimeter therethrough to cause the discharge to substantially fill said elongated cross section.
